UNITED STATES PATENT OFFICE.

JAMES BARRETT, OF BOSTON, MASSACHUSETTS.

DESIGN FOR A SEWER-TRAP.

SPECIFICATION forming part of Design No. 31,637, dated October 10, 1899.

Application filed September 9, 1899. Serial No. 730,014. Term of patent 14 years.

To all whom it may concern:

Be it known that I, JAMES BARRETT, of Boston, in the county of Suffolk and State of Massachusetts, have invented and produced a new 5 and original Design for a Sewer-Trap, of which the following is a specification.

The characteristic features of the design may be described as comprising a generally rectangular or box-like portion surmounted 10 by a cap, a straight pipe end springing from one side of the box, and a doubly-bent or U-shaped pipe-length springing from the opposite side of the box, with one limb enlarged at the top part and surmounted by a cap.

15 The drawings which accompany and form part of this specification illustrate a sewer-trap of my design.

Figure 1 represents the trap in plan, and Fig. 2 represents the same in side elevation. 20 In the drawings the letter *a* designates the rectangular or box-like portion of the trap, *b* the straight pipe end springing from one side of the same at its lower portion, and *c* the bent pipe-length springing from the opposite side of the box *a* at about the middle thereof. Said box has an outstanding flange *a'* around its top part and a flanged cap or cover *d* surmounts the same.

25 The straight pipe end *b* has an enlargement *b'*, in the form of a band, a short distance from its junction with the box and an outstanding flange *b''* at the top of the band-

like enlargement, which is surmounted by a cap or core *e* of rectangular form. A flat base *f* is connected with the pipe end around 35 the bottom of the enlarged portion *b'* thereof by right-angle webs *f'*, and the extremity of the pipe end is slightly enlarged, as shown at *g*. The middle portion of the bent pipe-length *c* drops considerably below the lower line of 40 the box *a*, and a flat base *h* in the plane of the base *f* is united with said portion of the pipe-length, webs *h'* extending between the latter and the base. The extremity of the bent pipe-length is in the form of a corrugated bell *i*, with a boss *i'* on top having a hole *i''*. The inner top portion of the outer limb of the bent pipe-length in rear of the 45 said bell is enlarged into box-like form, as shown at *j*, and a short neck *j'* springs from 50 the top of the same, with a flange *j''* around its top surmounted by a flanged cap *k*.

Having thus described my invention, what I claim as new and original is as follows:

The design for a sewer-trap substantially 55 as herein shown and described.

In testimony whereof I have signed my name to this specification, in the presence of two subscribing witnesses, this 25th day of August, A. D. 1899.

JAMES BARRETT.
